ATTORNEY.

UNITED STATES PATENT OFFICE.

LUDWIG FRIEDRICH, OF PITTSBURG, PENNSYLVANIA.

GLASS-WORKER'S TOOL.

SPECIFICATION forming part of Letters Patent No. 606,200, dated June 28, 1898.

Application filed May 28, 1897. Renewed May 2, 1898. Serial No. 679,549. (No model.)

To all whom it may concern:

Be it known that I, LUDWIG FRIEDRICH, a citizen of the United States, residing at Pittsburgh, in the county of Allegheny and State of Pennsylvania, have invented certain new and useful Improvements in Glass-Workers' Tools; and I do hereby declare the following to be a full, clear, and exact description of the invention, such as will enable others skilled in the art to which it pertains to make and use the same, reference being had to the accompanying drawings, which form a part of this specification, in which—

Figure 1 is a plan view of a tool embodying my invention. Fig. 2 is a longitudinal central section of the same. Fig. 3 is a detailed view of another form of chaser. Fig. 4 is a horizontal section on line $x-x$ of Fig. 2. Fig. 5 is an inverted plan of cap.

My invention relates to improvements in glass-working tools, and particularly to a device for completing bottle-necks after the body of the bottle has been blown.

My invention is in the nature of an improvement of the device shown in Letters Patent No. 509,214, granted to me November 21, 1893, whereby the device is more readily operated, and, furthermore, new functions can be performed by said improved device.

I will now describe my improvement, reference being had to the accompanying drawings, forming part hereof, in which like letters indicate like parts wherever they occur.

Referring now to said drawings, A is a chaser having a conical point a and a forming portion a' , which may be provided either with a screw-thread, as shown in Figs. 1 and 2, or with longitudinal or other desirable projections, as shown in Fig. 3. Adjacent to said forming portions said chaser, toward the upper end thereof, is provided with an annular projection or rim a^2 , the lower face a^3 of which is adapted to finish the top of the bottle. The rear portion of the chaser is tubular and is adapted to receive the spindle B, the lower end of which terminates in the annular rings or projections b' and b^2 , between which are formed raceways for the reception of the ball-bearings c and c' . In the end of said spindle, extending longitudinally of the same, is formed the socket d , in which the

pin e projects. Said spindle intermediate its length is also provided with annular projections f and f' , between which are formed raceways for the reception of ball-bearings g , and immediately to the rear of said last-mentioned projections with radial projections h h , adapted to engage in corresponding recesses i in the cap C, the lower end of said cap being screw-threaded to engage the upper threaded ends of the tubular portion of the chaser A, as shown in the drawings. The upper end of the spindle is screw-threaded and passes through an orifice in the upper end of the spring-handle formers D, being secured in said orifice by the small nuts j j . Said spring-handled formers D are provided with jaws arranged to force the glass against the forming portion a' of the chaser A, whereby the inside portion of the bottle is caused to take the desired impression from the forming portion of the chaser, which impression may be screw-thread or a series of alternate impressions and projections, accordingly as said forming portion is made. The jaws of said former are also provided with inwardly-extending groovers k k , which are adapted for use in forming a groove on the outer surface of a bottle, as in making a non-refillable bottle in which the stopper is cemented in place and which must be broken off at such groove in order to empty the bottle, or the jaws may be otherwise shaped to the outside of the bottle-neck, as may be desirable.

At that part of each jaw just below the annular projection a^2 is formed a shoulder l l , the shoulders being so formed that when the spring-handles are pressed together they will meet and inclose the lower tubular portion of the chaser, which passes between, while the annular projection will pass into recesses in the shoulders. Just below the shoulders l l each end of the spring-handled former is provided with an orifice or hole, through each of which a guide-rod n is passed. These guide-rods carry guide-ring o , which is provided with an annular recess for the reception of ball-bearings p p .

The operation of my device as thus far described is as follows, viz: The bottle is first blown, then headed and placed in my device by inserting the coned point a of the in-

side chaser into the neck of the bottle, forcing it open until the forming portion a' is within the neck of the bottle, the top end of the neck bearing tightly against the surface a^3 of the projection or rim a^2 . By pressing together the spring-handles and at the same time rolling the bottle in a snap the jaws force the glass firmly and closely against the forming portion a' . When the jaws are thus closed, the inside chaser is free to rotate, the length of the spindle B being such that its radial projections $h h$ will be pushed up into the tubular portion of the chaser and out of engagement with the recesses in the cap C when the annular projection a^2 is in its recesses in the shoulders ll . When the neck has been formed, the spring-handles may be opened, thus releasing the annular projection a^2 from the shoulders ll , whereupon by holding the device with the chaser downward the latter will drop, so that the recesses in the cap C and the radial projections $h h$ will engage and thus lock the chaser to the spindle and to the former. In this way the chaser may be either unscrewed from the bottle-neck, if internal screw-threads have been formed, or pulled from it, if ridges or projections have been made upon it.

On the surface or lower face a^3 of the projection a^2 , heretofore mentioned, suitable letters or marks may be formed, whereby when the bottle-neck is brought against said surface its top end will be impressed with such letters or marks, which may be raised or intaglio, as desired.

Having described my invention, what I

claim, and desire to secure by Letters Patent, is—

1. In glass-workers' tools, the combination with a pair of spring-handles having jaws, of a chaser, the rear or upper portion of which is tubular, and the forward portion thereof conical in shape; a spindle adapted to project into the tubular portion of said chaser; a cap slipped over said spindle, and clutch mechanism arranged on said spindle and in said cap for the purpose of locking said spindle, cap and chaser, substantially as herein described.

2. In glass-workers' tools, the combination with a pair of spring-handles having jaws, of a chaser provided with a forming portion, and a collar or projection adjacent to said forming portion; a spindle adapted to project into the upward portion of said tubular portion of said chaser; said spindle carrying ball-bearings arranged at both ends of the tubular portion of said chaser; a cap adapted to slip over said spindle; means carried by said spindle and said cap to lock said spindle, cap and chaser, and a guide-ring having ball-bearings arranged in an interior annular groove or recess therein, substantially as herein described.

In testimony that I claim the foregoing I hereunto affix my signature this 7th day of May, A. D. 1897.

LUDWIG FRIEDRICH. [L. S.]

In presence of—
JOHN M. JONE,
C. O'DONNELL.
